UNITED STATES PATENT OFFICE.

WALTER J. HERSCHEDE AND WALTER EBERHARDT, OF CINCINNATI, OHIO.

CHIME-ROD HOLDER FOR CLOCKS.

Application filed September 6, 1921. Serial No. 498,821.

To all whom it may concern:

Be it known that we, WALTER J. HERSCHEDE and WALTER EBERHARDT, citizens of the United States of America, and residents 5 of Cincinnati, in the county of Hamilton and State of Ohio, have invented a new and useful Improvement in a Chime-Rod Holder for Clocks, of which the following is a specification.

10 An object of our invention is to provide a mounting or holder for chimes of clocks and similar instruments, wherein greater timber and resonance, and better tone qualities are attained than are attained by the use of the 15 mountings known to us.

Another object is to attain a more musical and a more mellow chime, of longer and freer vibration.

These and other objects are attained by 20 the means described herein and disclosed in the accompanying drawings, in which—

Fig. 1 is a front elevation of the chime mounting embodying our invention.

Fig. 2 is a side elevation, part in section, 25 of the device shown in Fig. 1.

The holder A comprises a massive base a which is adapted to be secured upon a wall of a clock, or similar instrument, and from which extends a massive intermediate portion, vibration bar, or standard a' at the upper or free end of which is formed a massive shoulder a^2 . A rib a^3 extends centrally of the base and vibration bar, and merges into the massive shoulder a^2 . A massive head a^4 30 is mounted above the shoulder and has formed through it bores a^5 , the lower portion of which bores are enlarged, and in the upper ends of which bores are seated the chime rods or tubes B. The rods B are 35

struck by the hammers of an actuating mechanism in a manner well known in the art. 40

We have found that the construction disclosed herewith enhances the tone qualities and attains the objects stated.

What we claim is:

45 1. A chime rod holder comprising a base, a head adapted to fixedly seat chime rods, and a vibrating bar spacing the head and the base.

2. A chime rod holder comprising a massive base, a massive head adapted to seat chime rods, and a massive vibrating bar extending from the base, supporting the head and spacing the head from the base. 50

3. A chime rod holder comprising a massive base, a vibrating bar mounted at one of its ends upon the base, a massive shoulder formed at the other end of the vibrating bar, and a head mounted on the shoulder adapted to seat chime rods. 55

4. A chime rod holder comprising a base, a vibrating bar mounted at one of its ends upon the base, a shoulder formed on the other end of the vibrating bar, a rib extending over the base and vibrating bar and merging into the shoulder, and a head adapted to seat chime rods mounted on the shoulder. 60

5. A chime rod holder having an elongated massive standard, a base and a mounting for fixedly seating chime rods, all means formed 65 integral.

In testimony whereof, we have hereunto subscribed our names this 23rd day of August, 1921.

WALTER J. HERSCHEDE.
WALTER EBERHARDT.
